UNITED STATES PATENT OFFICE

THEODORE J. SCOFIELD, OF JACKSON, MICHIGAN, ASSIGNOR TO THE SPARKS-WITHINGTON COMPANY, A CORPORATION OF OHIO

BEARING FOR ELECTRICAL CONDENSERS

Application filed November 8, 1929. Serial No. 406,880.

This invention relates to electrical gang condensers such as are used in radio sets. One of the objects of the invention is to construct the bearings of the condenser so that the rotor plate and shaft assembly can be readily placed in position. 5

Another object of the invention is to construct the bearing contacts so that there will be good electrical spring contact between the 10 rotor shaft and the frame of the condenser.

Another object is to arrange the bearing so that there is continual frictional pressure to insure that the rotor will stay in the adjusted position regardless of jars or vibrations to 15 which it may be subjected while in use.

Other objects of the invention will appear in the following specification, reference being had to the drawings in which:

Fig. 1 is an elevation of a gang condenser 20 used in radio sets.

Fig. 2 is an end view of the condenser frame as viewed from the right of Fig. 1.

Fig. 3 is a view of the bearing plate.

Fig. 4 is an end view of the bearing plate 25 shown in Fig. 3.

Fig. 5 is an elevation of the compression plate of the bearing.

Fig. 6 is a view of the condenser with the shaft and rotor assembly being placed in 30 position.

Fig. 7 is a horizontal section view of the right-hand end bearing as shown in Fig. 1.

Fig. 8 is a view of the spring contact for the left-hand end of the rotor shaft as shown 35 in Fig. 1.

Fig. 9 is a longitudinal section taken on the lines A—A of Fig. 8.

Gang condensers used in radio sets are precision instruments and the mechanical 40 movement of the rotor plates in respect to the stator plates must be correct or else undesired variations in capacity or even short-circuits will result. It is necessary to have the rotor shaft revolve in a snug fitting bearing at each end for this reason. It is also 45 necessary to have good electric contact between the rotor shaft and the frame of the condenser to conduct the signal currents.

To permit the ready insertion of the rotor 50 in the condenser one of the bearings of the

rotor shaft is made separate from the frame of the condenser. The shaft 1 of the rotor has flange or side bearing member 2 thereon near one end, as shown clearly in Figs. 6 and 7. A hole 3 is formed in the end member 4 of the condenser frame sufficiently large to permit insertion of the shaft and this flange 2 when the rotor assembly is inclined at a considerable angle such as shown in Fig. 6, for example. No bearing contact is made 60 with this hole 3 and the size of such hole is immaterial so long as it is large enough to permit the flange 2 to be inserted with the rotor plates clearing the stator plates.

When the rotor shaft is assembled in the 65 rotor bushings 5 a fibre washer 6 may be placed on the inside of the flange 2.

The rotor assembly is pushed to the right, as shown in Fig. 6 sufficiently to permit the end 8 of the shaft to enter a snug bearing hole 70 9 in the end 10 of the condenser frame. While this operation is being performed the rotor plates would be positioned to project upwardly away from the stator plates, as shown in the drawings. 75

The fibre washer 7 may then be pushed on the right-hand end of the shaft 1, and brass bearing plate 11 is slipped over this end of the shaft. The hole in this bearing plate makes a smooth fit with the rotor shaft. This 80 plate 11 is half-punched at 12 in the two opposite corners to form protuberant dowels 13 which fit into depressions 13' into end 4 of the condenser frame. These dowels in conjunction with impressions in the end member 85 properly line the bearing plate 11 with the bearing hole 9 to hold the shaft in proper position. Screws 14 are passed through holes 15 in the bearing plate and are threaded into the end member 4 to tightly clamp the 90 plate against the end member of the condenser. Slotted plate 16 (see Fig. 5) is dropped into position with the slot 16' around the shaft 1. It is then slid to the right until the screws 14 pass through the 95 holes 17. Springs 18 are placed on these screws and nuts 19 are threaded on to the screws to compress the springs and force plate 16 against the fibre washer 6. With this arrangement the flange 2 on shaft 1 is 100

- forced to the right by the springs and frictionally engages the fibre washers 6 and 7 so that sufficient friction is obtained to always hold the rotor shaft in any position in which it is turned while allowing sufficient freedom to manipulate the shaft for tuning purposes. If it is necessary to remove the rotor shaft and the assembled rotor plates the operation just described would be reversed.
- 10 In order to insure good contact between the rotor shaft and the frame of the condenser a connecting member 20 (Fig. 8) is used. This consists of a strip of good conducting metal such as spring brass having a slotted opening 21 in one end, preferably of oblong form, to permit adjustment and a hole 22 in the opposite end slightly smaller than the end of the shaft 8. This hole is stamped so as to draw a protruding ring 23 to furnish a good bearing surface with the rotor shaft and a slot 24 is punched through this end to permit it to spring apart sufficiently to receive the end of the shaft and thus furnish spring contact therewith. This member 20 is placed over the end of the shaft 8 and the other end is fastened to the end plate 10 by means of screw 25 which passes through the opening 21 and is threaded into the end plate 10.
- 30 Any form of indicating drum 26 may be used on the other end of shaft 1 and any form of rotating means may be employed. I prefer to use the drum and rotating means shown in the application of Theodore J. Scofield and William D. Miner (case #2-1) Serial No. 398,864, filed October 11, 1929, but I have not shown these in this application as they form no part of the invention claimed in this application.
- 40 Having described my invention, what I claim is:
1. In electrical condensers, a frame, a shaft, a side-bearing flange on said shaft near one end, an end member on said frame having an opening adapted to permit the entry of said flange and shaft at an angle thereto, a bearing member fastened to said end member and fitting on one end of said shaft outside of said flange, a plate fastened to said end member and engaging the inside of said flange, and a bearing member for the other end of said shaft.
  2. In electrical condensers, a frame, a shaft, a side bearing flange on said shaft near one end, an end member on said frame having an opening adapted to permit the entry of said flange and shaft at an angle thereto, a bearing fastened to said end member and fitting on one end of said shaft outside of said flange, a plate having a slot adapted to fit over the shaft and means to resiliently clamp the said plate against the inside of said flange.
  3. In electrical condensers, a frame, a shaft, a side bearing flange on said shaft near one

end, an end member on said frame having depressions and an opening adapted to permit the entry of said flange and shaft at an angle thereto, a bearing fastened to said end member and fitting on one end of said shaft outside of said flange and having lugs fitting in said depressions, a plate having a slot adapted to fit over the shaft, and means to resiliently clamp the said plate against the inside of said flange.

4. In electrical condensers, a frame having a hole therein, a shaft, a flange on said shaft, said flange being small enough to enter said hole at an angle thereto, a plate fitting over said shaft on one side of said frame, a plate fitting over said shaft on the other side of said frame, bolts passing through said plates and frame, springs on said bolts, bearing against one of said plates, and nuts to compress said springs and clamp said plates against the sides of said flange.

In testimony whereof I have signed my name to this specification this 5th day of November, 1929.
